BUILDING CONSTRUCTION

Frank H. Alcott, Jamaica, N. Y.

Application January 5, 1933, Serial No. 650,227

5 Claims. (Cl. 20—1)

Heretofore it has been common practice to construct the outer walls of frame buildings of matched members arranged in clapboard or tongue and groove style, horizontally of the building. These members have been used principally as an outer enclosure of the building and have usually been applied outside of sheathing boards which have been affixed to the upright or stud structure. The tongue and groove construction has, however, generally formed no practical part of a supporting structure of the edifice.

It has also been known that flooring, roofing, wainscoting, sheathing, etc., might be constructed of tongued and grooved members in order to obtain a closer and more airtight fit between the various constructional elements. This type of construction has likewise been limited to secondary or accessory structure,—that is, structure separate and apart from the structural skeleton or framework of the building.

One reason why tongue and groove construction has not been utilized as supporting structure is probably because of the fact that it has heretofore not been known how a tongue and groove arrangement might be adapted and utilized successfully to carry out this purpose.

It is an object of the present invention to produce composite tongue and groove structure adapted not only for use for flooring, roofing, wainscoting, sheathing, and other accessory structure, but for supporting framework as well. The invention makes it possible to construct buildings of a minimum number of similar prefabricated sections, each composed of a tongued and grooved or similar matched combination and without employing additional members for structural advantage (as, for instance, increased stiffness and bending strength) other than wood or metal pins, dowels or composite splines and dowels of determinate cross-section and number. These combined matched elements thus perform a double function of supporting structure and accessory structure.

The invention is susceptible of being used with both standard and special types of heavy flooring, roofing, decking and similar tongued and grooved and/or splined plank or timber members. These members may be arranged in a novel manner whereby they are adapted to carry and support axial loads vertically as columns. They may also be arranged to carry loads horizontally as floor and roof systems. These advantages may be obtained without the necessity of employing the items usually essential to the structural framework.

In the drawing, Fig. 1 is a perspective view of a novel tongue and groove plank arrangement adapted for use as a wall structure of a building; Fig. 2 is a sectional view of an arrangement of tongued and grooved members as customarily assembled; Fig. 3 is a sectional view of the same tongued and grooved members but reassembled for use as a wall or bearing partition construction similar to that shown in perspective in Fig. 1; Fig. 4 is a diagrammatic view of a portion of a building constructed in accordance with the principles of the present invention; Fig. 5 is a fragmentary view of an ordinary floor section; and Fig. 6 is a fragmentary view of a floor section constructed in accordance with the principles of the present invention and comparable in strength to that of the floor section shown in Fig. 5.

As an example of the novel combination embodied in the present invention, the following consideration will be given to a wall construction in which the same may be utilized.

Instead of constructing a wall of the usual studding sheathed on one or both sides for lateral rigidity, I use (see Fig. 1) thick dressed and matched planks 10, preferably of standard size and form. Each edge of these planks is provided with off-center grooves 11 and tongues 12, or with suitable grooves in which splines or keys may be inserted. Instead of matching these members in the ordinary way with their surfaces flush with one another, as in Fig. 2, I reverse each alternate plank end for end and match the tongues (or splines) into the groove of the adjacent members. In this manner a staggered arrangement such as is indicated in Fig. 1 is obtained, giving a cross section such as is indicated in Fig. 3. For the reason that the increased load-carrying capacity of this structure as a bearing wall or partition, or as a floor system (as will hereinafter be explained) cannot be made entirely to depend upon the friction and lateral sheer value of the tongues (or splines) within the grooves, dowels 13, as shown in Figs. 1 and 6, are recessed into the edges of the matched workings. These are of a cross-section and length and are spaced sufficiently close together rigidly to secure the members together and thus to effect the continuity and resistance to displacement required for the composite structure in the bearing wall and/or the floor system in which it is to be incorporated. A sill 14 having a groove 17 may be provided in order that the ends of the members may be provided with a satisfactory foundation, the ends of the members 10 being provided with tongues 55

which upon assembly of the various members will be in proper alignment to fit into the groove 17. The upper ends of the wall may be provided with a plate 15 suitably rabbeted, and tongued as 5 at 16 so that it may match solidly over the upper ends of the vertical members 10, and into their grooves 11a.

With a construction as indicated above, an increase over-all thickness of from 25 to 37½% 10 over the net thickness of the ordinary tongue and groove construction is obtained and the section modulus of the construction is increased 33½% to 50%.

Assuming that the members 10 comprise 8" 15 planks having a net thickness of 2", the moment of inertia about the neutral axis x-x (Fig. 2) is represented by the formula

$$20 \quad I = \frac{bd^3}{12}$$

where I equals the moment of inertia of a rectangular cross section, b the breadth (in this case 16 lineal inches) of the section, and d the depth or net thickness of the plank, in this case 2".

Substituting the above constants in the basic equation, we get

$$30 \quad I = \frac{16 \times 2^3}{12} = 10\% \text{ biquadratic inches.}$$

With the staggered construction of the present invention, the same 2" planks when combined as indicated in Figs. 1 and 3, form a wall 25% to 37½% greater in total thickness than the planks themselves, and consequently that much thicker than a wall constructed of the tongue and groove members associated in the ordinary way as depicted in Fig. 2. The staggered arrangement effects a compound section with its neutral axis coincident with the gauge line of the off-center tongues and grooves. For instance, as indicated in Fig. 3, the outer sides of the planks 10 will be equidistant from the neutral axis y-y and the total thickness of the wall will be twice the greatest distance between the axis and the outer edge of each plank. Thus, when sheathing is placed on the outside of the composite structure and the inside if sheathed and/or lathed and plastered, the total thickness of the wall is considerably thicker than could be obtained from similar construction in which the outer faces of the planks are flush and in the same plane.

In order that the moment of inertia of the above construction may be compared with that 55 of the ordinary construction previously computed, the following computation is given. By recognized principles of mechanics, it is a fact that the moment of inertia of any compound section with respect to any axis is equal to the sum 60 of the moments of inertia of its several sections plus the area of these sections multiplied by the square of the distance between their respective centers of gravity and the neutral axis of the whole figure. Thus, ΣI_c is equal to

$$65 \quad I_1 + I_2 + A_1 \times h^2 + A_2 \times h^2,$$

where

I_c is equal to the moment of inertia of the composite figure,

70 I_1 is equal to the moment of inertia of one component part;

I_2 is equal to the moment of inertia of the other component part,

A_1 is equal to the area of the section of the 75 first component part,

A_2 is equal to the area of the section of the second component part;

h is equal to the distance between the neutral axis and the centers of gravity of the areas A_1 and A_2 , which in the example is the same in each case. For tongued and grooved planks of the form and dimensions described, this distance may be $\frac{3}{8}$ ".

Substituting the known values in the above 10 formula, we have

$$I_c = \frac{8 \times 2^3}{12} + \frac{8 \times 2^3}{12} + (8 \times 2) (\frac{3}{8})^2 +$$

$$15 \quad (8 \times 2) (\frac{3}{8})^2 = 5.33 \times 2 + 2.25 \times 2,$$

whence I_c is equal to 15.16 biquadratic inches.

It is apparent, therefore, that the moment of inertia of my novel wall construction, shown in Figs. 1 and 3, is 15.16 biquadratic inches as compared with that of 10.66 for a wall construction depicted in Fig. 2 made up by the normal fitting together of tongued and grooved members. This amounts to an increase of 4.50 biquadratic inches or

$$20 \quad \frac{4.50}{10.66} = 42.2\%$$

increased strength. It is apparent also that with greater thicknesses of material, with greater offsets or with narrower planks, even greater increases in the moment of inertia may be obtained.

The invention may also be used in floor or roof structures. For floor structure a composite or built-up arrangement may be utilized by using relatively smaller beam members in order to interlock with and support the floor planking, which latter is advantageously constructed in tongue and groove or other matched fashion. Referring to Figs. 5 and 6, wherein illustrative measurements of the members are indicated, Fig. 5 shows an ordinary floor construction made up of 2" x 10" joists 20 on which ¾" sheathing boards 21 are laid. In Fig. 6 I have shown 3" x 7" beam members 22 of considerably less depth, into which 2" x 7" planks 23 are framed, the planks 23 being parallel to and flush with the tops of the beams 22.

In the case of Fig. 5, the moment of inertia may be easily calculated:

$$50 \quad I = \frac{bd^3}{12} = \frac{2 \times 10^3}{12} = 166.6$$

and S, its section modulus is

$$55 \quad \frac{I}{\frac{1}{2}d} = \frac{166.6}{(10 \div 2)} = 33.3$$

In Fig. 6, however, the moment of inertia is a combination of that of its several parts about a modified neutral axis z-z. By taking moments about a line w-w through the bottom edge of the beam 22, which is taken as a 3" x 7" member, the distance C_1 , between this neutral axis and the line w-w may be found to be

$$65 \quad C_1 = \frac{A_1 h_1 + A_2 h_2}{A_1 + A_2}$$

A_1 =area of the floor plank section, $b \times d$

h_1 =height of its center of gravity above w-w

A_2 =area of the beam stem, $b' \times d'$

h_2 =height of its center of gravity above w-w, 70 whence

$$C_1 = \frac{16 \times 2 \times 6 + 3 \times 5 \times 2\frac{1}{2}}{16 \times 2 + 3 \times 5} = \frac{192 + 37.4}{32 + 15} = 4.875"$$

From the above it may be seen that the moment 75

of inertia about the neutral axis $z-z$, 4.875 inches above and parallel to the line $w-w$ is

$$I_e = I_1 + I_2 + A_1(h_1 - C_1)^2 + A_2(C_1 - h_2)^2$$

$$5 \quad I_1 = \frac{bd^3}{12} = \frac{16 \times 2^3}{12} = 10.66$$

$$I_2 = \frac{b'd'^3}{12} = \frac{3 \times 5^3}{12} = 31.25$$

10 Or as qualified:

$$(h_1 - C_1) = 6 - 4.875 = 1.125$$

$$(C_1 - h_2) = 4.875 - 2.5 = 2.375$$

$$15 \quad A_1 \times 1.125^2 = 32 \times 1.125^2 = 40.80$$

$$A_2 \times 2.375^2 = 15 \times 2.375^2 = 84.50$$

$$I_e = 167.21$$

Since S = section modulus =

$$20 \quad \frac{I}{C_1}, S = \frac{167.21}{4.875} = 34.4$$

Thus, the novel floor construction of the invention enables a composite structure to be made which has a considerably greater section modulus than that of the ordinary construction for the same depth flooring. In addition, the flooring construction described, like the wall construction previously alluded to, may be made in the factory and delivered on the job in built-up units adapted to be fitted together with facility. Compared with the ordinary construction which comprises merely relatively thin sheathing nailed across the top edges of the joists, the present construction gives a continuity and homogeneity of a truly composite figure and is greatly advantageous in giving additional stiffness to the construction.

Fig. 4 is a diagrammatic view of one way in which the wall construction illustrated in Figs. 1 and 3 may be utilized. The sections 32 are placed in position on sills 31 which may be supported by a foundation 38. Over the first group of sections 32, the metal anchor plate 33 may be fitted, or a wood plate 45, as shown previously in Fig. 1, the section 32 being preferably of a length equal to the height of one story of the building. The next group of sections 32' may be arranged upon the plate 33. Floor systems, as in Fig. 6, may be utilized or ordinary joisted floors may be used.

What I claim is:

50 1. A building construction comprising a plurality of similar interlocking plank members,

tongues and grooves on opposite longitudinal edges of said plank members adapted and arranged to match and fit the respective grooves and tongues of each similar adjacent member, said tongues and grooves being uniformly offset from a plane described through the middle of the edge portions of each plank, each alternate plank being reversed end for end so that the faces of adjacent members are out of alignment, and means extending through said longitudinal edges rigidly connecting said members together.

2. A building construction comprising a plurality of similar matched plank members, uniformly offset matching means on the longitudinal edges of each member, each of said members being rigidly connected with its adjacent members and assembled so that each alternate plank is offset laterally from a plane through the center lines of said matching means.

3. A composite structure comprising a plurality of similar plank members each provided with tongues along one longitudinal edge and corresponding grooves along the other, said tongues and grooves being spaced a uniform distance away from a plane passing through the middle of said edges, the center of gravity of each adjacent plank being on opposite sides of a plane through the center lines of the said tongues and grooves, and means for securing adjacent members rigidly with one another.

4. A building construction comprising a plurality of similar side and end matched interlocking plank members, workings on opposite longitudinal edges of said plank members adapted and arranged to match and fit one with another, said workings being uniformly offset from a plane described through the middle of the edge portions of each plank, each alternate plank being reversed end for end so that the faces of adjacent members are out of alignment, and means for securing each plank rigidly to its adjacent plank.

5. A building construction comprising a plurality of interlocking plank members, uniformly offset tongues and grooves on the longitudinal edges of each member, connecting means extending through said edges, and holding said members in non-slipping relationship, said members being assembled so that each alternate plank is offset laterally from a plane through the center lines of said tongues and grooves.

FRANK H. ALCOTT.
